UNITED STATES PATENT OFFICE.

CHARLES S. KING, OF NEW ROCHELLE, NEW YORK, ASSIGNOR TO SANFORD NARROW FABRIC CO., OF NEW YORK, N. Y., A CORPORATION OF NEW YORK.

DESIGN FOR AN EDGING.

53,740.

Specification for Design.

Patented Aug. 26, 1919.

Application filed February 12, 1919. Serial No. 276,659. Term of patent 14 years.

To all whom it may concern:

Be it known that I, CHARLES S. KING, a citizen of the United States, residing at New Rochelle, in the county of Westchester and State of New York, have invented a new, original, and ornamental Design for an Edging, of which the following is a specification, reference being had to the accompanying drawing, which shows a strip of edging in elevation.

I claim:—

The ornamental design for an edging, as shown.

CHARLES S. KING.
